Gilkison Manufacturing Co., Elyria, Ohio, a cor-
poration of Ohio

Application September 4, 1940, Serial No. 355,396

7 Claims. (Cl. 155—194)

This invention relates to chair construction and particularly to metal chairs involving stamped back rests and seats and a bent or formed supporting frame therefor.

The present improved chair may be considered in the nature of an improvement over or as a further development of the type of chair disclosed in my prior copending application Serial Number 294,185, which has become Patent No. 2,263,209. In the present instance, the seat and back are connected to the main supporting frame in a manner such that they may be quickly and easily knocked down or assembled without the use of tools and without removing bolts and like connecting members. Convenience and ease in assembling and disassembling the seat and back frame with respect to the main supporting frame is an important feature in that it reduces the cost of shipping and also materially reduces the cost of assembling the chair at the point of retail distribution, since by removing the seat and back, these parts may be nested into a compact bundle as may also the main supporting frames.

An important object of the present invention therefore is to provide a chair of the all metal type wherein the seat and back may be quickly and easily knocked down for shipping and storage purposes and reassembled in a like manner, to thereby materially reduce the cost of the chair.

Another object is to provide a chair of the knock down type wherein the parts may not only be quickly and easily assembled and disassembled but when in assembled relation provide a firm and stable support having no projections which might catch the clothing of or injure an occupant.

A further object is to provide an all metal chair of the type utilizing a stamped seat and back frame which may be manufactured at a relatively low cost without sacrificing comfort and quality.

The foregoing and other objects of the invention will become apparent in view of the following description taken in conjunction with the drawings wherein:

Fig. 1 is a longitudinal sectional view of a chair constructed in accordance with the features of the invention;

Fig. 2 is an enlarged detailed view of one of the back and side arm connecting joints;

Fig. 3 is a detailed view of the detachable connection between the seat and front supporting frame;

Figs. 4, 5 and 6 are schematic views illustrating the method of assembly.

Referring to the drawings in detail, one of the main supporting side frames is generally indicated at 10 and is shown as being made of spring steel bar stock but may be tubular or any other preferred shape, each side frame comprising a runner or base 11, a front upright 12 and side arm rest 13. The side frames 10 may be cross connected and braced by members 14 and 15 which are preferably riveted, welded or otherwise permanently connected to the said frame members. Corner braces 16 may also be used for rendering the structure more rigid at the front of the chair.

The seat and back are preferably made up of sheet metal stampings. The seat is generally indicated at 17 and has downwardly extending marginal portions 17a at the sides and a front 20 downwardly and outwardly curved portion 17b. At the point where the front wall 17b joins the side 17a the frame is preferably formed with a substantially flat or straight portion 18 to facilitate insertion in a receiving slot formed in a manner to be described.

The back of the seat has the edge rolled or curled as at 19, forming part of a hinge joint, the other part being provided by a similar rolled or curled portion 19a formed on the lower edge 25 of the back.

The back, generally indicated at 20, has the metal at its marginal portions shaped to provide side walls 20a, and in each of these side walls is an elongated substantially vertical slot 21 adapted to detachably receive therein a lug 22 which may be suitably connected to, or conceivably formed integrally with, the upper rear end of each arm rest 13. The lug is formed with a neck portion 22a, note Fig. 2, so that the lug 30 may be inserted in the slot when in registration therewith and then rotated to locked position.

The joint between the front frame uprights 12 and seat is preferably provided by connecting a lug or bracket 23 to each of the uprights 12, said lug being offset to form an open slot 24 adapted to receive the portion 18 of the seat. As will be noted, this connection may be made by simply pressing the seat downwardly to force the portions 18 of the seat into the slots 24.

Figs. 4, 5 and 6 successively illustrate the method of assembly. Assuming the frames 10 are connected in assembled relation, the back 20 may then be placed in a horizontal position bringing the lugs 22 into registration with the

slots 21, the arms being easily spread to accommodate such insertion. The back is then given a quarter turn so that it moves to its normal or correct position of use. The seat 17 is then brought into position so that the rolled edges constituting the joints 19, 19a are engaged, and the back is then held steady while the seat is pulled up in a substantially horizontal position and snapped in place in the slots 24.

To disassemble or remove the seat and back from the supporting frame, the front of the seat is first pulled up from the slots 24, then moved rearwardly behind the front cross member 15, whereupon it may be lifted out of its roll lock connection with the back. The back may then be turned to a horizontal position, permitting the lugs 22 to clear their slots 21.

To ensure a tight connection between the lug 22 and the side walls 20a of the back, the latter is formed with longitudinal indentations or grooves 25 on opposite sides of each of the slots 21, note Figs. 1 and 2, causing the metal at this point to assume a bevel and conform to the contour of the neck 22a of the lug 22 when the parts are in assembled relation. When the back is rotated from a horizontal position to its normal upright position, the connection automatically tightens, or the parts assume a snug fit due to the particular shape of the metal within the region of the slots. This construction also tends to strengthen the side walls of the back.

It will be noted that no bolts, screws or nuts are involved in the knock down and assembling operations, and hence no tools are required. This renders the task comparatively simple, so that labor costs are practically nil. The advantages of ease in knock down and assembling are not only confined to the manufacture, sale and distribution of chairs of this type, but are also important from the standpoint of use, since it enables a user also to fold and nest the chairs.

It will be noted that the joints are all protected by the framework of the chair, so that there are no protruding parts which would tend to catch the clothing or otherwise annoy an occupant of the chair.

It will be understood that certain changes in construction and design of the improved chair may be adopted without departing from the spirit and scope of the invention as defined by the appended claims.

What is claimed is:

1. A metal chair comprising side supporting frames having base portions, front uprights and arm rests, a seat and back formed of sheet metal, the back having the marginal portions thereof shaped to provide side flanges, said side flanges having elongated slots therein and said arm rests being provided with lugs adapted to register with and engage in said slots when the back is in a position at an angle to its normal position of use and become locked in the slots when the back is rotated to normal position of use, means pivotally and releasably suspending the seat from the back frame, and means carried by said uprights providing a detachable connection for said seat.

2. A chair comprising main supporting frames, one at each side of the chair, each frame including a base portion or runner, a front upright and an arm rest, a seat and back formed of sheet metal, the metal at opposite sides of the back being formed with elongated slots extending substantially longitudinally of the back and the arm rests being provided with lugs adapted to regis-

ter with said slots when the back is turned at an angle to its normal upright position and to lock in said slots when the back is returned to its normal upright position, means carried by the front uprights of the frame members providing in conjunction with said uprights upwardly opening recesses and the metal at the front of the seat being shaped to engage in said recesses, the lower portion of the back and the rear portion of the seat being shaped to provide inter-engaging joint members pivotally and releasably suspending the seat from the back, whereby the seat and back may be removed from the frame members by raising the seat clear of said recesses and swinging the back at an angle to its normal upright position and the seat and back then separated one from the other.

3. A chair comprising side supporting frames each having a base portion or runner, a front upright and an arm rest, a seat and back formed of sheet metal with outwardly facing side walls, the opposed side walls of the back each being formed with an elongated slot extending substantially longitudinally of the back and said arm rests each having a lug member shaped to engage in said slots when the back is turned at an angle from its normal upright position and to lock in said slots when the back is returned to its normal upright position, the front uprights of the supporting frame each having connected thereto a member defining in conjunction with the upright a vertically open recess and the metal at the front of the seat being shaped to engage in said recess to releasably support the front of the seat on said upright, the marginal metal at the base of the back and the rear end of the seat being shaped to provide a releasable pivoted suspension joint between the seat and back, whereby the seat and back may be removed from the supporting frame without the use of tools by raising the front of the seat clear of said recesses and then swinging the back at an angle to its normal upright position to release said lugs or bosses from said slots.

4. An all metal chair comprising resilient main supporting frame members, one at each side of the chair, each frame member including a base portion or runner, a front upright portion and an arm rest portion, a seat and back formed of pressed sheet metal with the metal at the margins thereof shaped to provide outwardly facing side walls, the opposed side walls of the back each being formed with an elongated slot extending longitudinally thereof and said arm rest each having connected thereto an elongated lug having a neck portion, the lugs registering with said slot when the back is turned at an angle to its normal upright position and locking in said slots when the back is rotated to its normal upright position, the front uprights each having connected thereto a member defining in conjunction with its upright a vertically open recess and the front wall of the seat being formed with portions adapted to engage in said recesses to releasably support the front of the seat on said uprights, the metal of the seat between said recess engaging portions being bent arcuately outwardly beyond the plane of the uprights, the metal at the lower edge of the back and the rear end of the seat being curled to provide a releasable pivoted suspension joint between the seat and back, the seat and back being removable from the supporting frame by raising the front of the seat clear of said recesses and then swinging the back at

an angle to its normal upright position to release said lugs or bosses from said slots.

5. A metal chair comprising side supporting frames each having a base portion, a front upright and an arm rest, a seat and back formed of sheet metal, the back having the marginal portions thereof shaped to provide side walls, said side walls having elongated slots therein extending longitudinally of the back and said arm rests being provided with lugs adapted to register with and engage in said slots when the back is in a position at an angle to its normal upright position of use and become locked in the slots when the back is rotated to normal position of use, the metal on opposite sides of said slots being formed with longitudinal depressions or grooves to cause the metal to conform to the shape of and tightly engage the lugs when the back is rotated to its position of use and to also strengthen the metal, means pivotally and releasably suspending the seat from the back frame, and means carried by said uprights providing a detachable connection for said seat.

6. A chair comprising a supporting frame structure including runners, front uprights and arm rests, a sheet metal seat and back carried by the frame structure, coacting means at the lower portion of the back and the rear portion of the seat providing a releasable joint connection therebetween and whereby the seat is pivotally suspended at its rear from the back, the back being provided with side members having elongated

slots therein and said arm rests being provided with lugs adapted to register with and engage in said slots when the back is in a position at an angle to its normal position of use and become locked in the slots when the back is rotated to normal position of use, and means carried by said uprights providing a detachable connection for the front of the seat.

7. A chair comprising a supporting frame structure including front uprights and arm rests, a sheet metal seat and back carried by the frame structure, the lower portion of the back and the rear portion of the seat each being shaped to provide integral members engageable for relative rotation to provide a hinge joint and releasably suspending the seat from the back when engaged, the back having means at opposite sides thereof coacting with means carried by the arm rests providing a connection between the back and arm rests releasable through relative angular movement of the back with respect to said rests, means on the front uprights providing therewith upwardly opening recesses, the metal at the front of the seat being shaped to engage in said recesses, whereby the seat and back may be removed from the main frame structure by raising the front of the seat clear of said recesses and turning the back at an angle to its normal upright position and the seat and back then separated one from the other.
